UNITED STATES PATENT OFFICE.

CHARLES PUTMAN McCLELLAN, OF FALL RIVER, MASSACHUSETTS.

FOLDING BOAT-TOP.

1,052,076.

Specification of Letters Patent.

Patented Feb. 4, 1913.

Application filed January 19, 1912. Serial No. 672,142.

To all whom it may concern:

Be it known that I, CHARLES P. McCLELLAN, a citizen of the United States, residing at Fall River, in the county of Bristol and State of Massachusetts, have invented certain new and useful Improvements in Folding Boat-Tops; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to tops for auto boats, launches and the like, and has for its object to provide a simple and efficient top which can be quickly and easily set up into operative position and furled or folded quickly, easily and compactly when the same is not in use.

With this object in view the invention consists in the novel construction and arrangement of the bows for supporting the boat top, and the invention also consists in the novel construction for mounting the bows.

The invention also consists in certain other novel details of construction and in combinations of parts, all of which will be first fully described and afterward specifically pointed out in the appended claims.

Referring to the accompanying drawings: Figure 1 is an elevation illustrating a small motor boat and the boat top applied thereon and in open or operative position. Fig. 2 is a similar view showing the boat top in a furled or folded position. Fig. 3 is a fragmentary perspective view illustrating the mounting of the bows. Fig. 4 is a side elevation illustrating the boat top and details for holding the same in open or operative position. Fig. 5 is a side elevation illustrating the boat top in a furled or folded position.

Like numerals of reference indicate the same parts throughout the several figures in which;

1 indicates a motor boat of any size, design or construction, the size of the boat being immaterial as far as this invention is concerned as the top or spray hood can be quickly and easily applied to any open boat.

2 indicates the boat top which is preferably constructed of a suitable cotton duck

or drill such as is usually employed for tents, awnings or the like, it being seen that the texture be closely woven in order to form a water-proof device. The bows to which the top fabric is secured are preferably arranged in groups 3 and 4, the forward group 3 comprising a plurality of bows, two being shown in the accompanying drawings. The forward group of bows 3 comprise a vertical bow 5 and a forwardly raking bow 6, which forwardly raking bow 6 is preferably pivoted to the vertical bow 5 at the point 7 as clearly shown in the drawings. The after group of bows 4 comprise a vertical bow 8 and an after raking bow 9, which raking bow 9 is pivoted to the vertical bow 8 at the point 10 as clearly shown in the drawings, the arrangement of the two groups or bows being identical in this particular.

Suitably arranged on the waterway or decking of the boat surrounding the cockpit thereof and preferably attached to the combing of the cockpit is the mounting 11 for the top or spray hood, said mounting comprising a forward bracket 12 and an after bracket 13, both brackets 12 and 13 being provided with flanges 14 and 15 for connection with the deck or waterway 16 and combing 17 of the boat by means of wood screws, bolts or other approved fastenings, and connecting the two brackets 12 and 13 is a longitudinal guide rod 18, it being of course understood that this construction is duplicated on each side of the boat. Arranged on the forward bracket 12 and extending outwardly therefrom at right angles thereto is a stud 19 to which stud 19 is connected a pivoted end 20, said pivoted end 20 being bifurcated as shown in Fig. 3 to straddle the reduced end of the stud 19 as is clearly apparent from the drawing. Upon this stud 19 the vertical bow 5 of the forward group 3 is mounted, the end of said bow 5 being provided with a perforation 21 through which the stud 19 passes. It will be understood from this specification that the term "bows" comprise also the metal mountings to which the wooden bows proper are attached, which metal mountings are designated by the letter A, the wooden bows proper being suitably connected to the metal mountings A by means of screws, rivets or other approved fastenings as is clearly shown in the drawings.

Referring now to the after group of bows

4 and in this connection particularly to Figs. 3 and 4 it will be seen that the vertical bow 8 is pivoted to a clip or yoke 22, which clip or yoke encompasses the longitudinal guide 18 and which is freely slidable thereon, and it will also appear that the upper end of the rear bracket 13 which carries the rear end of the longitudinal guide 18 extends a short distance above said guide and is provided 10 near its extreme end with a notch 23. It will also appear from Figs. 3 and 4 that a hook 24 is provided on the vertical bow 8 at the bottom thereof, which hook 24 is designed to engage the extension 25 of the rear bracket 13 in the manner as illustrated in 15 Fig. 4.

Secured to the raking bows 6 and 9 of each group of bows are adjustable straps 26 and 27, said straps passing from the center of the said raking bows downwardly to the forward and after deck of the boat, snap hooks 28 being preferably provided on the bottom ends of the straps 26 and 27 which engage eyes 29 secured to the deck of 20 the boat in order to facilitate ready operation of the top the said straps 26 and 27 being provided with a simple take-up construction as illustrated at 30 in order to quickly and readily adjust the lengths of 25 the straps 26 and 27 to conform to the height of the top, while a similar strap 60 lends rearwardly from the deck to the bow 5.

Having thus fully described the several 30 parts of the invention as applied to folding tops the operation of the invention is as follows: The mounting 11 being applied and secured to the boat in the manner as shown and described the top is arranged in operative position by securing the forward adjustable strap 26 in the manner as shown in Fig. 4, the after group of bows 4 being slidably by means of the yoke 22 on the longitudinal rods 18, said after group of 40 bows are moved into position shown in Fig. 4 until the hook 24 of the after group of bows passes over and engages the extension 25 of the rear bracket 13, and when in this position the rear securing strap 27 is hooked to the after deck of the boat in the manner illustrated in Fig. 4. When the top has thus been arranged in position the straps 26 and 27 are adjusted in order to draw the raking bows 6 and 9 into their 50 proper position so as to effectually open the top and to maintain the same in a smooth unwrinkled position. The top being thus set up the same is entirely permanent and cannot be moved out of its open position 60 until the rear strap 27 is unhooked or slackened away to allow the hook 24 on the after group of bows to become disengaged from the rear bracket 13 as shown in Fig. 3. When the rear group of bows are in this 65 position the same are moved forwardly in

the longitudinal guide rods 18 until said rear group of bows engage the forward group of bows 3 and when all of the bows are at the forward ends of the longitudinal rods 18 all of said bows are folded forwardly upon the forward deck of the boat in the position as shown in Fig. 5 which neatly and compactly folds or furls the top in the position as shown in such manner that the top is entirely out of the way of the occupants of the boat and in no sense interferes with the proper handling or steering of the boat and is in ready position to be instantly set up into operative position as shown in Fig. 4.

Having thus fully described the invention it is at once obvious that many immaterial changes or modifications in the details of construction can be employed without departing from the spirit of this invention and I consider myself clearly entitled to all such changes or modifications as fall within the scope of the appended claims.

What I claim as new and desire to secure by Letters Patent of the United States is:—

1. A top of the character described comprising longitudinal guide rods, supporting brackets therefor at each end of said guide rods, a vertical bow pivoted to the supporting bracket at one end of said guide rods, a bow pivoted to said bow, a slideable yoke arranged on each of said guide rods, a bow pivoted to each of said slideable yokes, a hook on said last mentioned bow attached to engage the supporting bracket on one end of each of said guide rods to hold said bow and said slideable clip against movement of said guide rods, a bow pivoted to said last mentioned bow and a suitable covering arranged on said bow, substantially as described.

2. A top of the character described comprising longitudinal guide rods, supporting brackets therefor at each end of said guide rods, a vertical bow pivoted to the supporting brackets at one end of said guide rods, a slideable yoke arranged on each of said guide rods, a bow pivoted to each of said slideable yokes, a hook on each of said last mentioned bows arranged to engage the supporting brackets at one end of the said guide rods to hold said bow and said slideable clip against movement on said guide rods, and a suitable covering arranged on said bows, substantially as described.

3. A top of the character described comprising longitudinal guide rods, supporting brackets therefor at each end of said guide rods, a vertical bow pivoted at one end of said guide rods, a pivoted bow, means for effecting a sliding connection between said last mentioned pivoted bow and said guide rods, a hook on said last mentioned pivoted bow arranged to engage the supporting brackets at one end of said guide rods to

hold said last mentioned bow against movement on said guide rods, and a suitable covering arranged on said bows, substantially as described.

- 5 4. A top of the character described comprising longitudinal guide rods, a vertical bow pivoted at one end of said guide rods, a slide-
able yoke arranged on each of said guide rods, a bow pivoted to said slideable yokes, a
10 hook on said last mentioned bow, an ele-
ment at one end of each of said guide rods

adapted to be engaged by said hook to hold said bow and said slideable yokes against movement on said guide rods, and a suitable cover arranged on said bows, substan- 15 tially as described.

In testimony whereof, I affix my signature, in presence of two witnesses.

CHARLES PUTMAN McCLELLAN.
